UNITED STATES PATENT OFFICE.

WARREN ALFRED JACOBUS, OF WOOD RIVER, NEBRASKA.

DIRECTION SIGNAL.

Application filed November 1, 1921. Serial No. 512,001.

To all whom it may concern:

Be it known that I, WARREN ALFRED JACOBUS, a citizen of the United States, and a resident of Wood River, in the county of 5 Hall and State of Nebraska, have invented certain new and useful Improvements in Direction Signals, of which the following is a specification.

My invention is an improvement in direction signals.

An important object of my invention is to produce a device of the above named character which is located near the steering wheel and is extremely simple to operate 15 thus eliminating the possibility of the operator's losing control of his car while attempting to give a signal with his hand.

Other objects and advantages of my invention reside in the novel construction 20 and arrangement of parts as will be more fully described and claimed, reference being had to the accompanying drawings, in which,

Figure 1 is a front view of the device 25 shown applied to an automobile, the signal arm being visible,

Figure 2 is a similar view of the device showing the signal arm hidden from view,

Figure 3 is a top view of the clamping 30 means and operating lever,

Figure 4 is a side view of the same,

Figure 5 is a detail of the collar,

Figure 6 is a detail of the signal arm,

Figure 7 is a sectional view of the dash 35 showing the device applied thereto,

Figure 8 is a detail of the adjusting means, and

Figure 9 is a section on line 9—9 of Figure 1.

40 In the drawings, 1 represents the steering post of the usual type. A collar 2 is securely held to the post a sufficient distance below the steering wheel 3 by any suitable means.

A sectional attaching band made up of 45 sections 4 and 5 is provided to loosely fit the annular runway 6 in the collar 2. The sections 4 and 5 have apertured ears 7 and 8 on one end as shown, which are secured within the tubular casing 9 by a bolt 10.

50 Section 5 of the band has its other end elongated to form an operating handle 11 having a knob 12. Another bolt and nut passes through apertures in the handle 11 and the ear 13 formed on section 4.

55 The tubular casing 9 is provided at the other end with a turned-down annular

flange 14 which engages the enlarged head 15 on one end of the plunger 16 operating within the casing. Thus the movement of the plunger is limited within the casing. 60 The opposite end of the plunger 16 is provided with a ball-shaped head 17 which is enclosed in a cup socket 18 formed in the signal arm 19. The plunger operates within the slot S, as shown. 65

A casing 20 is provided so that the signal arm 19 may freely slide therein back and forth at the wish of the operator.

Although the arm is shown as being operated from behind the dash-board 21 it is 70 to be understood that the same may be readily operated on the outer surface of the dash.

The ears 7 and 8 are so formed on the sections 4 and 5 respectively, that they permit the casing 9 to swing within limits as shown. It will be seen that the ball and socket joint formed by the head 17 and socket 18 and the hinge joint at 10 provide a structure that will permit a wider range 80 of adjustment to various makes of automobiles, and will also facilitate the operation of the device.

An electric lamp L is rigidly connected to the casing 20 and projects within the hollow arm 19 thereby causing light rays to be emitted through the window W in the arm 19 when the lamp is lighted. 85

The slot S' permits the arm to be moved backwardly and forwardly while the lamp 90 L projects therein.

In operation, when the operator of the automobile desires to make a turn to the left he grasps the handle 11 and by swinging the same around rotates the securing 95 band about the collar 2. As the casing moves from inoperative position as in Figure 2 to operative position as in Figure 1 the plunger moves backwardly and then forwardly to take the shorter radius during 100 the swing. Since the head 17 is securely held within the socket 18, the arm 19 will slide outwardly when the operator has moved the handle from the position shown in Figure 2 to that shown in Figure 1, thus 105 effecting the desired signal to operators of automobiles in the rear. At night the lamp L being lighted will illuminate the end of the arrow hand at W adapting the signal for day and night use. 110

Although I have herein shown and described only one form of device embodying

my invention, it is to be understood that various changes and modifications may be made herein without departing from the spirit of the invention or the spirit and scope of the appended claims.

I claim:—

1. A signal actuator comprising a lever rockable on a steering post of an automobile and having an adjustable arm whereby to conform the length of the arm to the varying arc of rocking movement of the lever.
2. In a signal actuator, a lever rockable on a steering post of an automobile, one of the arms of said lever being composed of telescopic sections and adapted for connection with a signal device whereby to conform the length of the arm to the varying arc of rocking movement of the lever when the lever is actuated.
3. In a signal actuator for use with signals on automobiles, an extensible actuating lever horizontally rockable on the steering post of the automobile, one of the arms of the lever being connected to the signal, the extensible actuating lever permitting the said arm to vary in length to compensate for the rocking movement of the lever, and an operating handle formed on the other arm.
4. A signal actuator adapted to be secured to the steering post of an automobile, comprising a collar rigidly secured to said steering post, a sectional securing band rotatably mounted on the collar, and having ears formed on each section, one section having an elongated portion forming an

operating handle, a casing pivotally secured to the ears at one end of the securing band and a plunger limited to reciprocate within the casing as the handle is operated, said plunger being adapted for connection to a signal device for operating the same.

5. A signal actuator comprising a casing, a plunger adapted for connection with a signal device, said plunger being movable within the casing, a sectional securing band pivotally connected with the casing and having an elongation on one section forming a hand grip, and a supporting collar having an annular groove for seating the band and adapted to permit the band to oscillate about the collar.

6. A signal actuator comprising a casing having an annular turned down flange at one end, a plunger having a head adapted to engage a signal device, said plunger being movable within the casing and restricted in movement by the flange, a securing band having ears projecting within the casing and pivotally connected with the same, a grip formed on the band, and a guide for the band for securing the same in operative position on a vehicle, said band being adapted to freely move over the guide when the handle is actuated.

7. A signal actuator comprising a bearing adapted for application to a steering post and a lever mounted between its ends on said bearing, being connected at its forward end with a signal and forming at its other end a handle whereby it may be operated.

WARREN ALFRED JACOBUS.
